UNITED STATES PATENT OFFICE

CHARLES DOLLACK, OF GLENDALE, LONG ISLAND, NEW YORK, ASSIGNOR TO THE JACOBS BROTHERS CO., INC., OF BROOKLYN, NEW YORK, A CORPORATION OF NEW YORK

SCALE

Application filed May 14, 1927. Serial No. 191,298.

This invention relates to an improved scale.

It is an object of the invention to provide a device of this character including a counterweight in convenient association therewith, this weight being readily associated with the proper scale parts, the structure achieving this purpose embodying relatively few parts individually rugged and readily 10 constructed and operated with minimum effort.

It is a further object of the invention to provide an improved scale pan structure to prevent an accidental displacement of the 15 pan while in use.

Other objects of the invention will in part be obvious and will in part appear herein-after.

The invention accordingly comprises the 20 features of construction, combination of elements and arrangement of parts which will be exemplified in the construction herein-after set forth, and the scope of the application of which will be indicated in the claims.

For a fuller understanding of the nature 25 and objects of the invention reference should be had to the following detailed description taken in connection with the accompanying drawings, in which:

Figure 1 is a side elevation of a scale embodying the improved construction of the present invention;

Fig. 2 is a partly fragmentary plan view thereof;

Fig. 3 is a fragmentary elevation of a slightly different form of construction from that shown in the preceding figures; and

Fig. 4 is an end view of certain of the construction shown in Fig. 3.

In these views the numeral 5 indicates the scale base, which, in the present instance, by means of arms 6 and pivots associated therewith, rockingly supports a beam 7; this beam being connected to a yoke 8, to the lower end

45 of which a dashpot (not shown) may be

attached. In the present instance, one arm of the beam is extended in the form of a pair of graduated bars 9, with the graduations of each of which a weight 10 registers, these weights being mounted for sliding movement upon the bars.

The second arm of the beam suitably mounts a pan-supporting member 11 carrying at its upper end radially-extending arms 12, the ends of which are upstruck as at 13 to extend substantially at right angles to their bodies. Resting within these arms is a pan 14, the side walls of which are slightly inclined to bear against the upstruck end- 55 portions 13 of the arms 12. Due to the fact that the latter have a certain inherent resiliency, it will be appreciated that while the pan is readily removable from its position its accidental movement will be virtually pre- 60 cluded for the reason that the wedge fit will 65 exist between the parts.

That end of the base 5 which underlies the bars 9 mounts a bracket 15 having at its upper end a plate formed with an opening 16 through which the extension 17 of the beam 70 projects. This bracket also mounts a plate 18 formed with an opening through which the shank 19 of a bottle weight 20 extends, the shank mounting a washer 21 of sufficient- 75 large size that it may not pass through the opening of the plate 18, and the upper end of the shank terminating in a hook 22; the inner edge of which provides a bearing surface. The outer end of the extension 17 is forked as at 23, and extending between the 80 arms of this portion is a pivot 24. As a consequence, the hook portion 22 may be disposed to extend over the pivot 24 as in Figs. 1 and 2; the weight 20 being thus free to suspend from the beam and exerting a mini- 85 mum amount of friction when the latter rocks.

In the form of construction shown in Figs. 3 and 4 the beam extension 17 is provided with a laterally-extending hook-shaped 90

pivot 25 overlying the opening of the plate 18, and the shank 19 of the weight terminates in an eyelet 26 for ready association with the extension 25; it being observed that the eyelet or rounded end of the shank is sufficiently large to prevent the same from slipping clear of the plate 18.

Thus, in both of the illustrated embodiments the scale may be used and the load weighed by means of the sliding weights. Under such conditions, the counterweight, in each instance, will be supported by the bracket 15, and accidental detachment of the weight from the scale parts will be prevented. An operator, upon finding that it is necessary to attach the weight of the beam, may achieve this simply by moving the former upwardly to a point at which its supporting structure is suspended by means of pivots 24 or 25.

Further, if a pan-supporting structure of the nature shown is employed it will be appreciated that an operator will not displace the pan by striking against the same, the pan being supported effectively and restrained against movement by means of the arms within which it nests.

Thus, among others, the objects of this invention have been accomplished, and since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A scale including a base, a beam rockingly mounted thereon, a counterweight, detachable means for operatively associating said weight with said beam, said weight being gripped by the hand and shifted to associate it with and remove it from association with the beam and means for preventing a removal of said weight from positions adjacent said base.

2. A scale, including, in combination, a rockingly-mounted beam, a fixed bracket extending adjacent thereto, a counterweight, means for suspending said counterweight from said beam, and means for preventing a detachment of said weight from said bracket.

3. A scale including a base, a beam rockingly mounted thereon, a bracket extending adjacent said beam, a counterweight, detach-

able means for operatively associating said weight with said beam, said weight being gripped by the hand and shifted to associate it with and remove it from association with the beam and means forming a part of said bracket for confining the movements of said weight.

4. A scale, including, in combination, a rockingly-mounted beam, a bracket extending adjacent thereto and formed with an opening, a counterweight having a portion extending through said opening and for detachable association with said beam, and an enlarged part forming a portion of said weight and of a size greater than said opening to prevent a detachment of said weight from the bracket.

5. A scale, including, in combination, a rockingly-mounted beam, a bracket extending adjacent thereto and formed with an opening, a counterweight having a portion extending through said opening and for detachable association with said beam, and an enlarged part forming a portion of said weight and of a size greater than said opening to prevent a detachment of said weight from the bracket, said enlarged part extending above the bracket opening, and said weight in its inoperative position being suspended by said bracket.

6. A scale, including, in combination, a rockingly-mounted beam, a bracket formed with an opening through which the end of said beam extends, a pivot member associated with the extended portion of said beam, an outwardly-extending portion forming a part of said bracket and being provided with an opening, a weight to be attached to said beam, and a shank forming a part of said weight and extending through said last-named opening and engaging said beam pivot.

7. A scale, including, in combination, a rockingly-mounted beam, a bracket formed with an opening through which the end of said beam extends, a pivot member associated with the extended portion of said beam, an outwardly-extending portion forming a part of said bracket and being provided with an opening, a weight to be attached to said beam, a shank forming a part of said weight and extending through said last-named opening and engaging said beam pivot, and an enlarged part forming a portion of said shank and of a size greater than said opening whereby upon said shank being detached from said pivot said enlarged part will bear against the outwardly-extending portion of said bracket to suspend said weight.

8. A scale including a base, a beam rockingly mounted thereon, a fixed bracket adjacent one end of such beam and connected to the base, an article-supporting member adjacent the opposite end of the beam, a counterweight, means for detachably supporting

said weight from the first named beam end,
means whereby said weight may be sup-
ported by said bracket and said weight being
adapted to be grasped manually and shifted
5 from a position at which it is supported by
said bracket to a position at which it is sup-
ported by said beam end and means associated
with said bracket to prevent movements of
said weight beyond predetermined positions.

10 In testimony whereof I affix my signature.
CHARLES DOLLACK.
